UNITED STATES PATENT OFFICE.

HENRY FRATERNALI, OF DOBBS FERRY, NEW YORK.

FOOT WARMER.

Application filed February 27, 1922, Serial No. 539,705. Renewed September 30, 1924.

To all whom it may concern:

Be it known that I, HENRY FRATERNALI, a citizen of Italy, residing at Dobbs Ferry, in the county of Westchester and State of New York, have invented new and useful Improvements in Foot Warmers, of which the following is a specification.

This invention relates to foot warmers, and the principal object is to produce a device of this nature which shall be so constructed as to give off the heat of its contents slowly thereby remaining warm for a comparatively long time, thus particularly adapting itself to use in hospitals, automobiles, etc.

With these and other objects in view, which will be more apparent as the specification proceeds, the invention resides in certain novel construction, the essential features of which are hereinafter fully described, are particularly pointed out in the appended claim, and are illustrated in the accompanying drawing, in which:

Figure 1 is a side elevation, partly in section, of my improved foot warmer in the preferred form for use in hospitals.

Figure 2 is a vertical sectional view of the same on line 2—2 of Figure 1.

Figure 3 is a view similar to Figure 1 but of the preferred form for use in automobiles.

Figure 4 is an end view of the form shown in Figure 3.

Like characters of reference indicate like parts in all views.

Referring to the drawing in detail, the reference character 10 represents a receptacle made of terra-cotta and formed with legs 11 and handles or ears 12. A neck 13 is preferably counter-sunk in the top, and is provided exteriorly with a screw thread to receive a metal cap 14. There is provided a cork or rubber gasket 15, and as the suction caused by the cooling of the liquid 45 would tend to maintain the gasket on its seat, I provide a wire or cord 16 provided

with a finger-piece 17 exteriorly of the device and with a button 18 interiorly, so that the gasket may be readily removed with the cap. A cover or cozy 19 may be placed over the device to keep the heat in. 50

While, as I have above said, the device is made of terra-cotta, it is also coated both inside and outside with enamel so as to give a polished, highly glazed finish. This finish 55 prevents or at least greatly retards the rapid escape of heat from the vessel. It is to be understood that hot water is used with the device, and that when the warmer is filled, it is first thoroughly washed inside and out 60 with hot water so that the terra-cotta body is thoroughly warmed. The form shown in Figures 1 and 2 is particularly constructed and designed for use in hospitals, while that shown in Figures 3 and 4 will be found 65 more adapted for use in automobiles and the like.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my 75 invention limited only by the appended claim.

What is claimed as new is:—

As a new article of manufacture, a foot warmer comprising a terra-cotta body 80 enameled inside and outside, a counter-sunk neck, a rubber stopper adapted to expand against the walls of the neck by virtue of the heat in said body for closing said neck, means for holding said stopper in position, 85 said means comprising a cap for screw threaded engagement with said neck and a pull cord secured to said stopper and extending through said cap.

In testimony whereof I have affixed my 90 signature.

HENRY FRATERNALI.
